ATTORNEY

UNITED STATES PATENT OFFICE.

WALTER F. YOUNG, OF MERRILL, WISCONSIN.

VIOLIN.

1,289,590.

Specification of Letters Patent. Patented Dec. 31, 1918.

Application filed May 8, 1917. Serial No. 167,232.

To all whom it may concern:

Be it known that I, WALTER F. YOUNG, a citizen of the United States, residing at Merrill, in the county of Lincoln and State 5 of Wisconsin, have invented certain new and useful Improvements in Violins, of which the following is a specification.

This invention relates to musical instruments, and more particularly to the class of 10 stringed instruments.

The primary object of the invention is to provide a stringed instrument similar to the ordinary violin, that can be cheaply and inexpensively manufactured to produce an 15 instrument of desirable resonant qualities and increased carrying power only found in an expensively constructed violin.

Another object of the invention is to produce an instrument of this character that 20 will entirely obviate the necessity of having a hollow body, such as is commonly employed in the ordinary violin.

Another object of the invention is to provide a musical instrument of this character 25 that will transmit the tone produced from the strings through a sound conveying duct toward the end of the instrument neck where the sound may be emitted through a horn.

30 The above and additional objects are accomplished by such means as are illustrated in the preferred embodiment and in the accompanying drawings, wherein like characters denote like or corresponding parts 35 throughout the several views, in which;

Figure 1 is a plan view of the instrument constructed in accordance with my invention.

Fig. 2 is a longitudinal section on the line 40 2-2 of Fig. 1.

Fig. 3 is a section on the line 3-3 of Fig. 1.

Referring to the drawing, wherein is illustrated the preferred form of my invention, 45 and in which like numerals of reference indicate corresponding parts throughout the several views, the body 1 is constructed from a suitable piece of any preferred material such as light wood. The body may be 50 shaped to resemble the ordinary violin if the same is desirable, but it is pointed out, that since no hollow interior is necessary, the body may be shaped to any preferred de-

sign. The neck 2 is constructed from any desirable material and is preferably shaped to 55 conform substantially to the well-known violin hand slide, so that players of the violin may find no difficulty in using the present invention. The neck, however, is provided with a longitudinal groove 3 which 60 is open for the greater portion of the length of the neck and is covered by the finger board 4, thus closing the groove and providing a part of the sound conveying duct 5. The enlarged end of the neck is fixed 65 to the forward portion of the body 1, this fastening being accomplished by a suitable joint, the parts being glued together in any preferred manner such as is commonly found in instrument construction of this 70 character.

A circular depression 6 is formed in the top surface of the body 1, and the center of the depression is at one side of the longitudinal center line of the body. Arranged 75 in this recess 6 is a diaphragm 7. Two annular rubber gaskets are arranged in the depression 6, and the marginal edges of the diaphragm are received between the gaskets so that the diaphragm is disposed substantially midway between the top and bottom of the recess or depression 6. It is to be noted that the outer annular wall of the depression 6 is cut away to provide a shelf 8, upon which the diaphragm rests. The 85 width of the gaskets is equal to the width of the shelf so that the exposed portion of the diaphragm is of substantially the same area as the bottom of the recess 6, this construction being clearly shown in Fig. 3 of the 90 drawing.

Communicating with the space 9, at the bottom of the recess is the sound receiving chamber 10 having communication with the passageway 11 which leads to the groove in 95 the neck, thus providing a continuous sound conveying duct from the space 9 to the end of the neck. The duct opens at the end of the neck below the scroll portion thereof, and is connected to the tube 12 which supports a horn 13 at its terminal; thus a direct passage is established between the horn and the diaphragm or space 9 in the body 1. 100

The tail-piece is fixed to the body in the usual manner and is joined to the strings 105 which overlie the finger board, and connect

to the pegs in the manner identical with the construction of the ordinary violin. It will be noted, by referring to Fig. 1 of the drawing, that the center of the diaphragm is disposed slightly to one side of the "G" string so that the bridge 14 has one end edge approximately alined with the center of the diaphragm. Fig. 3 of the drawing shows the bridge 14 mounted upon the pressure-regulating lever 15. The latter rests upon a support 16, which rests upon the top surface of the body 1, and may be moved to tilt the lever 15 at any desired angle to obtain the necessary adjustment for regulating the pressure. The outer end of the lever 15 is provided with an opening for receiving a screw 17 which is extended into the body 1, while a metal washer 18, and a rubber washer 19 are interposed between the top of the lever 15 and the head of the screw. It must be observed that when the strings are drawn taut across the bridge 14 the pressure on the end of the lever 15 will be considerable. Now, by virtue of the rocker support 16, the screw 17 may be adjusted to tilt the lever 15 on the rocker 16, and thus press upwardly against the strings until the end 20 of the lever 15 is properly disposed for the purpose of attaching the same to the diaphragm.

Fastened to the center of the diaphragm is a pin which extends upwardly and is loosely received in an opening in the end 20 of the lever 15. Surrounding the pin and interposed between the diaphragm and the end 20 of the lever is a rubber sleeve 21.

It will be apparent that the screw 17 may be adjusted to raise or lower the end 20 of the lever 15 against the pressure exerted by the strings, so that the diaphragm will be relieved of any excessive strain.

The sound receiving chamber permits the sound to be conveyed through the duct to the horn so that the volume of the tone is materially increased. The mellow tone thus produced is obtained from a comparatively cheap construction and the same has heretofore only been obtained through the medium of finely seasoned and expensive woods.

From the foregoing it will be observed that a very simple and durable musical instrument has been provided, the details of which embody the preferred form. I desire it to be understood, however, that slight changes in the minor details of construction may be made without departing from the spirit of the invention or the scope of the claims hereunto appended.

I claim:

1. In an instrument of the character described, the combination of a solid body shaped to simulate a violin body, a diaphragm mounted in the body, the latter having a sound-conveying duct terminating in proximity to the said diaphragm, and a neck

mounted on the body and provided with a sound-conveying duct communicating with the said duct in the body.

2. In an instrument of the character described, the combination of a solid body shaped to simulate an ordinary violin body and having a neck fixed thereto, a diaphragm carried by the body, the said body and the said neck having a sound conveying duct extending from the said diaphragm to the free end of the said neck, and a horn fixed to the neck and communicating with the said duct.

3. In an instrument of the character described, the combination of a solid body shaped to simulate an ordinary violin body and having its upper surface provided with a recess, a diaphragm mounted in the recess, a neck connected to the body and provided with a longitudinal passage-way open at each end and in communication with the said recess, and a horn mounted in the opposite end of the passage-way and projecting from the end of the said neck.

4. In an instrument of the character described, the combination of a solid body having a neck projecting therefrom, strings extending longitudinally of the neck and fastened to one end thereof and to the said body, a bridge supporting the said strings, a diaphragm mounted in the body, and means supporting the said bridge and connected to the said diaphragm whereby the pulsations of the strings will be communicated to the said diaphragm.

5. In an instrument of the character described, the combination of a solid body having a recess therein, strings disposed above the said body, a bridge supporting the strings to maintain them in spaced relation from the body, a supporting element carried by the body and supporting the said bridge and extended over the said recess, and a diaphragm disposed in the recess and connected to the said element.

6. In an instrument of the character described, the combination of a solid body having a circular recess at one side of its center, a bridge mounted upon the body, strings attached to the body and mounted on the said bridge, a pressure-regulating lever mounted on the body and adapted to tilt thereon and having one end extending over the center of the said recess and supporting the said bridge, a diaphragm mounted in the said recess, and means for connecting the said diaphragm to the end of the said lever whereby the diaphragm is vibrated.

7. In an instrument of the character described, the combination of a solid body having a recess formed therein, a pressure regulating lever, a support mounted on the body and disposed to support the said lever to permit tilting movement of the arm,

strings attached to the body, a bridge mounted upon the said lever and supporting the said strings above the body, a diaphragm arranged in the recess and connected to one end of the lever, means mounted on the body and connected to the said lever at the opposite end thereof to tilt the said lever on the support, the said body having a sound-

conveying duct communicating with the said recess.

In testimony whereof I affix my signature in presence of two witnesses.

WALTER F. YOUNG.
